UNITED STATES PATENT OFFICE.

JOHN GEHMAN, OF BRUTUS, MICHIGAN.

SAFETY DEVICE FOR ELEVATORS.

1,109,412.

Specification of Letters Patent. Patented Sept. 1, 1914.

Application filed November 7, 1912. Serial No. 730,075.

To all whom it may concern:

Be it known that I, JOHN GEHMAN, a citizen of the United States, residing at Brutus, in the county of Emmet and State of Michigan, have invented new and useful Improvements in Safety Devices for Elevators, of which the following is a specification.

My present invention relates to safety devices for elevators including governor mechanism operatively connected with braking means, to set the latter when the elevator car exceeds a predetermined speed in its descent.

The principal object of my invention is to provide means operable automatically, regardless of any other controlling mechanism of the elevator, and without attention by the car operator or passengers, to effect a stoppage of the car should it drop, or start to descend at an unsafe speed.

Other objects of my invention will appear in the following detailed description, taken in connection with the accompanying drawings forming a part of this specification, and in which drawings:

Figure 1 is a front elevation of the mechanism showing its application to a car. Fig. 2 is a cross sectional view on the line 2—2 of Fig. 1. Fig. 3 is an enlarged detailed view, partly in section, showing governor mechanism. Fig. 4 is an enlarged fragmentary sectional view illustrating the connection between the spindle and angle arm of the device.

In the drawings, where similar characters refer to similar parts, 4 designates a car body, of the type movable vertically in a shaft. Laterally of the car body, I provide upright parallel tracks 5, spaced apart from each other at opposite sides of the elevator shaft, and also an upright rack 6, with its tread at a right angle to the treads of tracks 5.

The car body 4 carries a frame 7, for mechanism to be subsequently described, and oscillatable depending guides 8, disposed laterally of tracks 5.

Movable toward or from tracks 5, and carried by guides 8, are brake shoes 9. These shoes are preferably carried by guides 8, so that they reciprocate transversely thereof, but are not rotatable. Each shoe is provided with a screw threaded recess 10, which recesses have a common axis and face each other.

Mechanism for moving shoes 9 simul-

taneously in counter directions, I have designated generally by 11. This mechanism may comprise a shaft 12, having ends screw threaded in opposite directions and complementary to the threaded recesses 10 of shoes 9, into which they extend, to move the shoes simultaneously in counter directions; arms 13 revolvably supporting shaft 12 and pendently supported from frame 7, the arms 13 and guides 8 being mounted for oscillatory movement; and, a gear 14, rigid with shaft 12, to be swung into mesh with rack 6, so that upon descent of the car, if gear 14 does mesh with said rack, shaft 12 will be rotated as indicated by arrows, separating shoes 9.

The frame 7 carries governor mechanism, designed generally by 15. This mechanism is preferably of that type having weights 16 suspended by links 17 from a collar 18 rigid with a spindle 19, this spindle being revolvably carried by frame 7. Links 20 connect balls 16 and a member 21 revolvable with spindle 12 and axially movable, or reciprocable thereon.

In order to operate governor mechanism 15 from rack 6, I provide gearing, designated generally by 22. This gearing may comprise a bevel gear 23 carried by frame 7, rigid with spindle 19; a meshing bevel gear 24; a pinion 25 to rotate gear 24; and a gear 26 meshing with pinion 25 and with rack 6. Thus, movement of the descending car rotates gear 26, which in turn successively rotates pinion 25, gear 24 and gear 23, which latter rotates spindle 19, the centrifugal action upon weights 16 causing them to separate, raising member 21.

Operatively connected with governor mechanism 15, I provide means for imparting movement of reciprocable member 21, to the mechanism 11, to render the same active. This means, designated generally by 27, preferably includes a lever 28 pivoted to frame 7, a link 29 operatively connecting one arm of lever 28 with one of the arms 13; a reciprocable spindle 30, revolvably carried by frame 7, accommodated at its upper end by a recess 31 in spindle 19 and operatively connected with member 21 as by lugs 32, so that reciprocation of said member 21 is imparted to spindle 30; and, angle member 33 operatively connecting spindle 30 and the other arm of lever 28, to oscillate the latter upon reciprocation of the former. Thus, as member 21 moves upwardly, due to centrifugal force acting upon balls 16, the spindle

30 is also raised, which movement causes lever 28 to move gear 14 toward rack 6, through link 29 and one of the arms 13. If speed of the car, in descent, is beyond a predetermined rate, the balls 16, raise member 21 sufficiently to bring said gear 14 into meshing relation with racks 6. The shaft 12 is then rotated as previously described moving shoes 9 into contact with tracks 5.

10 Suitable locking mechanism is provided to retain gear 14 in meshing relation with track 6, when governor mechanism 15 moves said gear to such relative position. This locking mechanism may comprise a pawl 35, pivoted to one arm 13, as at 36, and adapted to engage in notch 37, provided in frame 7, when said arm has been moved sufficiently to bring the gear 14 into meshing relation with rack 6.

20 From the foregoing, it is made manifest that I provide a safety device for elevators, including brake shoes adapted to frictionally engage suitable tracks, when the car, in descent, exceeds a predetermined speed.

25 It is of course obvious, that this mechanism is applicable to elevators of the type having an inclined path of movement, as well as those movable vertically.

Changes in details may be made without departing from the spirit or scope of my invention; but,

I claim:—

1. In a safety attachment for elevator cars, the combination with a vertical rack, of non-rotatable brake shoes supported by said car the said shoes being provided with complementary recesses, a shaft connecting said shoes, said shaft being threaded oppositely at its respective extremities to engage the complementary recesses of said shoes, and means operable at a predetermined speed of descent of said car and engageable with said rack for rotating said shaft to actuate said shoes, as and for the purpose set forth.

2. The combination with an elevator car, and an upright track and upright rack disposed laterally thereof, of a brake shoe carried by said car movable from or to contact with said track, means including a gear adapted to mesh with said rack to move said shoe into contact with said tracks during descent of the car, and second means including a gear meshing with said rack to move the said gear of said first-mentioned means into mesh with said rack when the car descends at a predetermined speed, substantially as and for the purpose set forth.

3. The combination with an elevator car, and upright tracks, disposed in parallelism, and an upright rack disposed laterally of the car, of brake shoes, carried by said car, one for each track movable from or to contact therewith, means including a gear adapted to mesh with said rack, to move said

shoes simultaneously in counter directions to contact with their respective tracks, and second means including a gear meshing with said rack, to move said first-mentioned gear into mesh with said rack when the car descends at a predetermined speed, substantially as and for the purpose set forth.

4. The combination with an elevator car, and an upright track and upright rack disposed laterally thereof, of a brake shoe carried by said car movable from or to contact with said track, means including a gear adapted to mesh with said rack to move said shoe into contact with said track during descent of the car, second means including a gear meshing with said rack to move the said gear of said first-mentioned means into mesh with said rack when the car descends at a predetermined speed, and locking mechanism for retaining said first-mentioned gear in mesh with said rack, when actuated by said second means, substantially as and for the purpose set forth.

5. The combination with an elevator car, and two upright tracks disposed in parallelism, and an upright rack disposed laterally of the car, of brake shoes, carried by said car, one for each track, movable from or to contact therewith, and each having a screw-threaded recess, said recesses facing each other with a common axis, a shaft having ends screw threaded in opposite directions, to fit into the said recesses of said shoes, a gear for rotating said shaft during descent of the car, adapted to mesh with said rack, and second means including a gear meshing with said rack to move the said first-mentioned gear into mesh with said rack, when the car descends at a predetermined speed, substantially as and for the purpose set forth.

6. The combination with an elevator car, and two upright tracks disposed in parallelism, and an upright rack disposed laterally of the car, of brake shoes, carried by said car, one for each track, movable from or to contact therewith, and each having a screw threaded recess, said recesses facing each other with a common axis, a shaft having ends screw threaded in opposite directions, to fit into the said recesses of said shoes, a gear for rotating said shaft during descent of the car, adapted to mesh with said rack, second means including a gear meshing with said rack to move the said first-mentioned gear into mesh with said rack when the car descends at a predetermined speed, and locking mechanism for retaining said first-mentioned gear in mesh with said rack when actuated by said second means, substantially as and for the purpose set forth.

7. The combination with an elevator car, and an upright track and upright rack disposed laterally thereof, of a brake shoe carried by said car movable from or to contact

with said track, means including a gear adapted to mesh with said rack to move said shoe into contact with said track during descent of the car, second means for moving 5 the said gear of said first-mentioned means into mesh with said rack, and governor mechanism operable from said rack, including a reciprocable member connected with said second means to operatively actuate the 10 same when the car descends at a predetermined speed, substantially as and for the purpose set forth.

8. The combination with an elevator car, and an upright track and upright rack disposed laterally thereof, of a brake shoe carried by said car movable from or to contact 15 with said track, means including a gear adapted to mesh with said rack to move said shoe into contact with said track during descent 20 of the car, second means for moving the gear of said first-mentioned means into mesh with said rack, governor mechanism operable from said rack, including a reciprocable member connected with said second 25 means to operatively actuate the same when

the car descends at a predetermined speed, and locking mechanism for retaining said gear in mesh with said rack when actuated by said second means, substantially as and for the purpose set forth. 30

9. In a safety attachment for elevator cars, the combination with a vertical rack bar, governor mechanism operable beneath said car, means engageable with said rack bar and having connection with said governor mechanism for actuating the latter according to the speed of movement of said car, mechanism normally disposed out of engagement with said rack, means actuatable at a predetermined speed of rotation of said 40 governor mechanism for bodily moving said last mentioned mechanism into engagement with said rack, and means operable by said last mentioned mechanism when in engagement with said rack to check movement of 45 said car, as and for the purpose set forth.

JOHN GEHMAN.
